CLOCK OR SIMILAR ARTICLE

William V. Judson, Westport, Conn., assignor to General
Electric Company, a corporation of New York

Filed Apr. 16, 1968, Ser. No. 11,473

Term of patent 3½ years

Int. Cl. D10—01

U.S. Cl. D42—7

Fig. 1.

Fig. 2.

Fig. 3.

Fig. 4.

FIG. 1 is a front elevational view of a clock embodying my new design;

FIG. 2 is a front perspective view thereof;

FIG. 3 is a rear elevational view thereof; and

FIG. 4 is a top plan view thereof.

The ornamentation partially shown in FIGS. 1 and 2 is understood to continue throughout the area between the clock face and the intermediate ornamental frame.

I claim:

The ornamental design for a clock or similar article, substantially as shown and described.
